Frank Zimecnik - INVENTOR.

UNITED STATES PATENT OFFICE.

FRANK ZAMECNIK, OF WASHINGTON, DISTRICT OF COLUMBIA.

OPERATING-TABLE.

1,378,930.

Specification of Letters Patent. Patented May 24, 1921.

Application filed October 20, 1920. Serial No. 418,204.

To all whom it may concern:

Be it known that I, FRANK ZAMECNIK, a citizen of the Republic of Czechoslovakia, who has declared his intention of becoming 5 a citizen of the United States, residing at Washington, District of Columbia, have invented certain new and useful Improvements in Operating-Tables, of which the following is a specification.

10 This invention relates to improvements in adjustable tables employed by physicians, surgeons and the like; more particularly by chiropractors when operating on patients, and has for one of its objects to improve 15 the construction and increase the utility and efficiency of tables of this class.

Another object of the invention is to provide a table of this class which will be comfortable to the patient, automatically 20 adjustable to the movements of the patient under treatment, and which will also automatically adapt itself to the degree of pressure applied by the practitioner.

With these and other objects in view, the 25 invention consists in certain novel features of construction as hereinafter shown and described and then specifically pointed out in the claims, and in the drawings illustrative of the preferred embodiment of the 30 invention:

Figure 1 is a side elevation, partly in section, of the improved table.

Fig. 2 is a plan view.

Fig. 3 is an elevation of the foot end of 35 the improved table.

Fig. 4 is a transverse section on the line 4-4 of Fig. 1.

Fig. 5 is a plan view with the cushions removed.

40 Fig. 6 is a sectional detail illustrating a modification in a portion of the construction.

Figs. 7 and 8 are detail views on a reduced scale illustrating another modification 45 in the construction.

The improved table comprises a head frame formed of corner posts 10, connecting upper stringers 11 and lower stringers 12, a foot frame formed of corner posts 13, 50 upper connecting stringers 14 and lower stringers 15, the head and foot frames being connected near their lower ends by longitudinal stringers 16.

The head frame is formed with its upper 55 lines sloping downwardly toward the foot and supports plates 17 in spaced relation

and cushioned, as shown at 18, the object to be hereinafter explained.

The upper lines of the foot frame are preferably horizontal, and resting upon the 60 posts 13 and the upper stringers 14 is a plate or board 19, the latter cushioned, as shown at 20.

The plate 19 is hingedly connected to the posts 13 nearest the head frame, as shown 65 at 21, so that it can be tilted as shown by dotted lines in Fig. 1. The hinges 21 have detachable pintles 22, so that the board can easily be detached to provide access to the spring mechanism when required.

The lower stringers 15 of the foot frame support a floor member 23, while the space between the posts 13 and stringers 14 and 70 15 are filled with panels 24 and a transverse partition 25 to form a cabinet or receptacle, the rear panel being hinged at 26 to form a door to the cabinet.

Pivoted at 27 in the inner posts 10 of the head frame is a head member 28 for a bar 29, the latter extending toward the foot 80 frame, as shown. Attached by screws 30 or the like to the bar 29 at its free end is a board or plate 31 having a cushion 32 on its upper face. The plate 31 is widest at 85 its rear end and converges toward the forward end, as shown in Fig. 2.

Attached by screws 33 or the like to the under face of the plate 31 are extension bars 34, the latter extended at their free 90 ends beneath the adjacent portion of the plate 19 and provided with wear plates 35.

Hingedly united at 36 to the adjacent member 11 of the head frame is a shorter plate 37 resting by its free end upon the bar 29 having an upholstered top 38, preferably supported by springs 39, as shown 95 in Fig. 1.

The plate 37 and the upholstering 38 is formed with recesses 40 in its side edges to render it more comfortable for the patient. 100

Attached to the sides of the rear or foot frame are plates 41, and pivoted at 42 to each plate is a bar 43, the bars being connected at their forward ends by a transverse member 44, the bars 43 bearing at 105 their free ends respectively beneath the extension bars 34. Each of the bars 43 is provided with a shorter member 45 spaced from the bar, and the shorter members connected by transverse supports 46.

The longer bars 43, shorter bars 45 and coupling members or supports 44 and 46

coact to form a relatively rigid frame swinging upon the pivots 42.

Mounted within the spaces between each of the bars 43 and its shorter bar 45 is a cam device 47, and extending from each cam device is a rod 48 terminating in a head or enlargement 49 and surrounded by a compression spring 50. The springs are relatively powerful and exert their force in action with the cam devices to maintain the bars 43 yieldably in a horizontal position, and correspondingly hold the larger bars 29 and 34 together with the plate 31 and cushion 32 yieldably in substantially horizontal position, and to automatically return them to normal position when released.

An additional expansion spring 51 is connected to one of the transverse members 46, and operates to supplement the action of the springs 50.

The plate 37 and its cushion 39, being supported by the bar 29, are moved upwardly and downwardly therewith, as will be obvious.

By this means supporting cushions 32 and 38 are yieldably supported and are returned automatically to their normal position when released.

The rear plate 19 and its cushion member 20 have a recess 52 in the forward edge to protect certain parts of the patient during certain manipulations of the operator.

Attached to the upper transverse member or support 46 is a knob or projection 53 adapted to engage the board or plate 19 when the bars 29 and 34 with their attached cushion 32 are depressed against the resistance of the springs 50 and 51 to swing the free end of the member 19 and its cushion 20 into the position shown by dotted lines in Fig. 1. This is an important feature of the improved table, as when the patient lies face down on the table, with the face upon the cushion members 18, the posterior region above the cushion 32, and the lower limbs upon the cushion 20, when pressure is applied to the lower part of the spinal column, the support 32 will yield downwardly and relieve the patient of undue jars or concussions, while at the same time the lower limbs will naturally rise when the intermediate

body portion is depressed, and by providing means whereby the supporting member 20 follows the lower limbs in their upward movement, the latter are effectually supported at all times.

The upward movement of the support 20 corresponds to the downward movement of the support 32, so that they coact to adequately support the body of the patient during all stages of the treatment.

While I have shown the springs arranged and applied beneath the free end of the extension members 34, they may be applied near the swinging end, as shown in Fig. 6, or at any other point desired.

The springs may also be applied as shown in Figs. 7 and 8.

What is claimed is:

1. A table device of the class described comprising a forward body support, a rear body support, a forward intermediate body support, a rear intermediate body support, means for yieldably supporting said intermediate body support, and means whereby the depression of the intermediate body supports causes the elevation of the rear body support.

2. A supporting frame including forward and rear standards in spaced relation, a forward body support upon said forward standard, a rear body support hingedly united to said rear standard, a bar swinging at one end from the forward standard and extended toward the rear standard, an intermediate body support hinged at one end to said forward standard and bearing at its free end upon said bar, another intermediate body support attached to said bar, and yieldable means for holding said bar and its attached body support in its upper position.

3. A table device of the class described comprising a forward body support, a rear body support a forward intermediate body support, a rear intermediate body support, means for yieldably supporting said intermediate body support, and means whereby the depression of the bar causes the rear body support to be elevated.

In testimony whereof I hereunto affix my signature.

FRANK ZAMECNIK.
